UNITED STATES PATENT OFFICE.

MELVON A. MARQUETTE, OF CHICOPEE FALLS, MASSACHUSETTS.

DESIGN FOR A TIRE.

60,692.

Specification for Design. Patented Mar. 21, 1922.

Application filed March 22, 1920. Serial No. 367,882. Term of patent 3½ years.

To all whom it may concern:

Be it known that I, MELVON A. MARQUETTE, a citizen of the United States, residing at Chicopee Falls, in the county of Hampden and State of Massachusetts, have invented a new, original, and ornamental Design for a Tire, of which the following is a specification, reference being had to the accompanying drawing, forming part thereof.

The drawing is a perspective view showing a portion of a tire embodying my design.

I claim—

The ornamental design for a tire as shown.

MELVON A. MARQUETTE
